(57) **CLAIM**

I claim the ornamental design for bow tie knot cover, as shown and described.

DESCRIPTION

FIG. 1 is a front elevational view of the bow tie knot cover with a reflective surface;

FIG. 2 is a left side view of the bow tie knot cover shown in FIG. 1; the right side view being a mirror image of the left side view;

FIG. 3 is a rear view of the bow tie knot cover shown in FIG. 1;

FIG. 4 is a top view of the bow tie knot cover shown in FIG. 1; the bottom view being a mirror image of the top view;

FIG. 5 is a front elevational view of a second embodiment of the bow tie knot cover;

FIG. 6 is a left side view of the bow tie knot cover shown in FIG. 5; the right side view being a mirror image of the left side view;

FIG. 7 is a rear view of the bow tie knot cover shown in FIG. 5;

FIG. 8 is a top view of the bow tie knot cover shown in FIG. 5; the bottom view being a mirror image of the top view;

FIG. 9 is a front elevational view of a third embodiment of the bow tie knot cover;

FIG. 10 is a left side view of the bow tie knot cover shown in FIG. 9; the right side view being a mirror image of the left side view;

FIG. 11 is a rear view of the bow tie knot cover shown in FIG. 9; and,

FIG. 12 is a top view of the bow tie knot cover shown in FIG. 9; the bottom view being a mirror image of the top view.

The broken lines in FIGS. 1–8 form no part of the claimed design.
